DESIGN FOR A TEXTILE FABRIC

Application filed November 7, 1932. Serial No. 45,794. Term of patent 3½ years.

To all whom it may concern:

Be it known that I, GUSTAV M. PULITZER, a citizen of the United States, residing at the city of New York, in the county of New York and State of New York, have invented a new, original, and ornamental Design for a Textile Fabric, of which the following is a specification, reference being had to the accompanying drawing, forming part thereof.

The figure is a plan of a textile fabric, showing my new design. The area within

the dot and dash lines shows one complete unit of the design. The repeats are arranged in vertical rows, and adjacent vertical rows are one half a complete unit offset so that the angle of the complete unit indicated by letter A corresponds with the angle B of one of the repeats in an adjacent vertical row.

I claim:

The ornamental design for a textile fabric, substantially as shown and described.

GUSTAV M. PULITZER.
